DESIGN FOR A MACHINE FOR OPENING CANS

Jean Otis Reinecke, Chicago, Ill., assignor to
Dazey Churn & Manufacturing Co., St. Louis,
Mo., a corporation of Missouri

Application February 26, 1944, Serial No. 112,731

Term of patent 14 years

(Cl. D22—2)

To all whom it may concern:

Be it known that I, Jean Otis Reinecke, a citizen of the United States, residing in the city of Chicago, county of Cook, and State of Illinois, have invented a new, original, and ornamental Design for a Machine for Opening Cans, of which the following is a specification, reference being had to the accompanying drawing, forming a part thereof.

In the drawing:

Fig. 1 is a top plan view of a machine for opening cans, showing my new design;

Fig. 2 is a side elevational view thereof;

Fig. 3 is a front elevational view thereof, and

Fig. 4 is a rear elevational view thereof.

I claim:

The ornamental design for a machine for opening cans, substantially as shown.

JEAN OTIS REINECKE.
